CLAIM

The ornamental design for a receiver for pet collar, as shown and described.

DESCRIPTION

FIG. 1 is a front and right side perspective view of a receiver for a pet collar, showing our new design, in a first embodiment.

FIG. 2 is another front and right side perspective view of the design of FIG. 1, at a slightly different angle.

FIG. 3 is a bottom perspective view thereof.

FIG. 4 is a front and left side perspective view thereof.

FIG. 5 is a front elevational view thereof.

FIG. 6 is a rear elevational view thereof.

FIG. 7 is a top plan view thereof.

FIG. 8 is a bottom plan view thereof.

FIG. 9 is a right side elevation view thereof.

FIG. 10 is a left side elevational view thereof.

FIG. 11 is a front and right side perspective view of the receiver for a pet collar, showing our new design, in a second embodiment.

FIG. 12 is another front and right side perspective view of the design of FIG. 11, at a slightly different angle.

FIG. 13 is a bottom perspective view thereof.

FIG. 14 is a front and left side perspective view thereof.

FIG. 15 is a front elevational view thereof.

FIG. 16 is a rear elevational view thereof.

FIG. 17 is a top plan view thereof.

FIG. 18 is a bottom plan view thereof.

FIG. 19 is a right side elevation view thereof; and,

FIG. 20 is a left side elevational view thereof.

(Continued)

The broken lines shown in the drawings depict portions of the receiver for pet collar that form no part of the claimed design.
